ELECTRICAL VIBRATING BACK MASSAGER

Samuel L. McNair, Overland Park, Kans., assignor to
Dazey Products Co., Kansas City, Mo.

Filed Mar. 13, 1974, Ser. No. 450,821

Term of patent 14 years

Int. Cl. D6—09; D28—03
U.S. Cl. D83—1 S

Fig. 1.

Fig. 2.

Fig. 3.

Fig. 4.

Fig. 5.

Fig. 6.

FIG. 1 is a top perspective view of an electrical vibrating back massager showing my new design;

FIG. 2 is a top plan view of same;

FIG. 3 is a side elevational view of same, the other side being substantially the same in appearance;

FIG. 4 is a bottom plan view of same;

FIG. 5 is an end elevational view of same from the right hand end of FIG. 2; and

FIG. 6 is an end elevational view of same from the left hand end of FIG. 2.

I claim:

The ornamental design for an electrical vibrating back massager, as shown and described.
